US0D1076027S

(12) **United States Design Patent** (10) **Patent No.:** **US D1,076,027 S**
(45) **Date of Patent:** **** May 20, 2025**

(54) **DRAIN PLUG**

- (71) Applicant: **Mingzhu Xu**, Shenzhen (CN)
(72) Inventor: **Mingzhu Xu**, Shenzhen (CN)
(**) Term: **15 Years**
(21) Appl. No.: **29/968,179**
(22) Filed: **Oct. 15, 2024**
(51) LOC (15) Cl. **23-01**
(52) U.S. Cl.
USPC **D23/260**
(58) **Field of Classification Search**

(57) **CLAIM**

The ornamental design for a drain plug, as shown and described.

DESCRIPTION

FIG. 1 is a front, right and top perspective view of a drain plug, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof, shown in an alternative, open configuration of use; and,

FIG. 10 is a perspective view thereof, shown in another alternative, open configuration of use.

The broken lines shown in the drawings illustrate portions of the drain plug that form no part of the claimed design.

1 Claim, 10 Drawing Sheets
